UNITED STATES PATENT OFFICE.

ROY VINSON COLLINS, OF NEW YORK, N. Y.

APPARATUS AND METHOD FOR OPERATING SWITCHES.

1,266,555.

Specification of Letters Patent.

Patented May 21, 1918.

Application filed May 13, 1913. Serial No. 767,244.

To all whom it may concern:

Be it known that I, ROY VINSON COLLINS, of New York, in the county of New York, and in the State of New York, have invented

5 a certain new and useful Improvement in Apparatus and Methods for Operating Switches, and do hereby declare that the following is a full, clear, and exact description thereof.

10 My invention relates to an apparatus and method for operating switches and has for its object to provide a switch automatically controlled by the condition of the motor circuit of an approaching car. If the car approaches the switch with its motor-circuit open, the switch will be set, if not already set, to send the car in one direction, as straight ahead; if the car approaches the switch with its motor-circuit closed, the

15 switch will be set, if not already set, to send the car in a different direction, as around a curve. Other and further objects of my invention are to provide a switch having the following characteristics:

20 The switch is controlled without stopping the car, but cannot be controlled by a car approaching the switch until a preceding car has passed the switch;

25 The operating mechanism may be placed above ground where it is dry and readily accessible for inspection or adjustment;

The operating mechanism is set in motion by a very light, quickly-acting part although the operating mechanism itself moves comparatively slowly;

30 The time of engagement between the car and the contactor device may be as short as desired, as the operation of the mechanism does not depend upon maintaining such engagement for any appreciable length of time;

35 The switch-operating motor (which may be of any desired type) is cut out automatically as soon as it sets the switch even though a car should stop in engagement with the contactor device; and

40 Both the apparatus and the method of operation are applicable to railroads of any type, although particularly advantageous for trolley railroads.

45 Other and further objects of my invention will be apparent from the following description of one embodiment thereof, and from an inspection of the accompanying dia-
50 grammatic drawings of said embodiment as applied to a trolley railroad, in which—

Figure 1 is a view showing an apparatus

embodying my invention with the operating mechanism in normal position,—that is, with the switch-operating motor at rest and the 60 parts in position to be controlled by an approaching car;

Fig. 2 is a view similar to Fig. 1 showing a trolley in engagement with the first contactor and with the car motor circuit open; 65

Fig. 3 is a view similar to Fig. 2 after the switch-operating motor has completed its movement;

Fig. 4 shows the parts with the trolley engaging the second contactor thereby causing 70 the main contact bars to return to normal position ready to be controlled by the next approaching car;

Fig. 5 is a view showing a trolley engag- 75 ing the first contactor with the car motor cir-
cuit closed;

Fig. 6 is a view similar to Fig. 5 after the switch-operating motor has completed its movement;

Fig. 7 is a longitudinal sectional view of 80 the first contactor; and

Fig. 8 is a transverse sectional view taken on line 8—8 of Fig. 7 looking in the direc-
tion of the arrows.

While I have illustrated my invention by 85 the best embodiment thereof known to me, my invention is not to be restricted to such embodiment, and is to be regarded as typical only of many possible embodiments and uses. 90

This embodiment consists of a contactor A located on the trolley wire (or other conductor), and with which the trolley (or other collector) of the car engages. The position of the switch-point is controlled 95 by the condition of the car motor circuit, that is, whether the car motor circuit is open or closed. The contactor is located ahead of the switch a sufficient distance to allow the mechanism time in which to throw the 100 switch before the car reaches it, even though the car be moving at maximum speed, and at the same time to permit the mechanism to operate slowly enough to prevent injury to the parts by a too sudden movement 105 thereof or to cause the switch to splash water on passers-by.

A second contactor B also is located on the trolley wire between the first contactor A and the switch, and at a point in advance 110 of the switch sufficient to allow the last wheel of the car to engage with or pass over the switch before the trolley engages with said second contactor.

Referring to Fig. 1, reference character 1 indicates a switch-point pivoted at 2. A link 3 is pivoted at one end to the switch-point, and at its other end is threaded 5 through a nut 4 swiveled on an arm 5 carried by a journal 5'.

Secured to said journal 5' is a lever 6, the ends of which are connected by wires 7 to a chain 8, which engages or is secured to a 10 suitable drum. These connecting parts ordinarily are underground, the wires 7 in the present embodiment being shown as passing through underground pipes. Any equivalent connecting means may be used. 15 Also secured to said sleeve or journal 5' is an arm 10 to which is pivoted a rod 9, the other end of which extends loosely through a fixed plate 11. A compression spring 12 is mounted on said rod between a shoulder 20 thereon and said plate 11, the arrangement being such that said spring 12 tends to hold lever 6 (and consequently the switch-point) in either of its two extreme positions (Figs. 1 and 3).

25 The drum engaged by chain 8 is provided with a gear 13 which meshes with a pinion 14' mounted on the armature of a switch-operating motor 14. The drum and the parts controlling its operation preferably 30 are mounted on a trolley or feed wire pole where they will be free from dampness and moisture.

35 Contactor A consists of a frame secured to the trolley wire W and having a lever 15 pivoted thereon at 16. A section 17 of said lever 15 is insulated from the frame, and from the trolley wire at that point. Fixed to said lever 15 is an arm 27 (Figs. 7 and 8) at the upper end of which is pivoted a movable contact 18 electrically connected with trolley wire W in any desired manner as 40 through its mounting and provided with a fulcrum pin 25 movably mounted in slots in arms 22 of a forked piece 21 pivoted to the frame at 23. Movable contact 18 also is provided with a finger 28 which projects toward a plunger 29 carried by the armature 30 of a solenoid or magnet 31 mounted on the frame. A compression spring 33 is 45 mounted on said plunger between a collar 32 thereon and a bracket 32' through which the plunger passes, the spring tending normally to retract the plunger from the path of said finger 28. A screw 34 limits the 50 retractile movement of the armature and is adapted to adjust the extent of such movement.

55 When trolley T engages lever 15, the upward pressure of said trolley lifts said lever 60 (Fig. 2) and its arm 27, thereby raising movable contact 18 and its fulcrum pin 25 in the slots in arms 22 of forked piece 21, so that movable contact 18 may engage either with stationary contact point 19 or stationary contact point 20 depending upon

whether the car motor circuit is open or closed. If the car motor circuit is open, movable contact 18 falls to the right and engages stationary contact point 19 (Fig. 2). If the car motor circuit is closed, movable 70 contact 18 falls to the left and engages stationary contact point 20 (Fig. 5), as finger 28 on contact 18 engages plunger 29, which is protruded by the energizing of solenoid 31, which is accomplished by a circuit closed 75 through trolley wire W, solenoid 31, insulated cables 92, 93, insulated section 17, and trolley T. This circuit is connected to trolley wire W at a point preferably removed from insulated section 17, as by cable 80 31', and if deemed preferable only a portion of this circuit need pass through solenoid 31.

As soon as trolley T passes lever 15, said lever falls to normal position, and movable contact 18 is returned to normal position 85 (Fig. 3).

Second contactor B consists of a frame 35 secured to trolley wire W and having a lever 36 pivoted thereon at 37. Fixed to said lever 36 is an extension 38 to which is pivoted a movable contact 39 connected electrically with trolley wire W and normally maintained in inoperative position (Fig. 1) by a shoulder 43 thereon adapted to rest on a shoulder 44 on frame 35. When lever 36 95 is raised by the upward pressure of trolley T engaging therewith, shoulder 43 on movable contact 39 is lifted above shoulder 44 on frame 35, thereby permitting movable contact 39 to engage stationary contact point 100 41 (Fig. 4).

The wiring and electrical connections for the control of the switch are illustrated diagrammatically in Figs. 1 to 6 inclusive.

Referring to Fig. 1, which shows the parts 105 in normal position, a vertical row of stationary contact points is illustrated as indicated at 45, 46, 47, 48, 49, and 50. At the right of said vertical row are two stationary contact points 51 and 52, and at the left 110 of said vertical row are two stationary contact points 53 and 54. A movable contact point 55 is carried by a link 56 attached to the upper end of a lever 57 which is pivoted at its lower end and is provided with a 115 weight arm 58 which tends to keep a roller 59 on an arm 60 in the path of a cam 61 mounted on gear 13. A similar movable contact point indicated at 63 is carried by a similar link, lever, and weight arm construction as indicated at 62, and which tends to keep the roller 64 in the path of a cam 65 also mounted on gear 13. These movable contact points may be connected to a wire 120 87 in any desired manner as by a flexible wire 88. A stop 57^a is provided to limit the inward movement of lever 57 and a stop 62^a is provided to limit the inward movement of the lever construction 62. A contact bar 66, pivoted at its lower end and 125

provided with a weight arm 67; and a similar contact bar 69, pivoted at its lower end and provided with a weight arm 70; are adapted to make proper connections between 5 said contact points. The movement of said bars is controlled by magnets or solenoids 68 and 71 respectively, acting in opposition to the respective weight arms of said bars. A pair of stationary contact points 72 and 10 73, are in like manner adapted to be connected by a contact bar 74, pivoted at its lower end and provided with a weight arm 75. The movement of said bar is controlled by a magnet or solenoid 76 acting in opposition to said weight arm 75. This last-named contact device will be referred to hereinafter as a "throw-off" device.

The connecting wires will not be described in detail, as their arrangement is believed to 20 be obvious to those skilled in the art from an inspection of their diagrammatic illustration in the drawings and from the following description of the switch operation.

In the present illustration, the apparatus 25 is arranged to set the switch for the curve if the trolley T engages contactor A with the car motor circuit closed, and to set the switch for straight ahead if the trolley T engages said contactor A with the car motor 30 circuit open. In other words, the motorman of an approaching car controls the switch by the position of his controller handle without stopping the car. If the switch point already is in proper position, it will remain 35 so; and if not, it will be thrown to proper position.

Assuming first in the embodiment illustrated, that a car approaches a switch set for the curve, (Fig. 1) and the motorman wishes 40 to set the switch for the straight track. The car will proceed by its own momentum under contactor A with the car motor circuit open and as the upward pressure of trolley T raises lever 15, movable contact 18 falls into 45 engagement with stationary contact point 19 (Fig. 2) in the manner described above. As said movable contact 18 is connected electrically with trolley wire W, a circuit is 50 closed through stationary contact point 19, wire 77, contact point 51, contact bar 66, contact point 52, wire 78, contact point 48, wire 79, magnet 71, wires 80, 81, and through resistance 82 to ground. This energizes magnet 71 thereby raising weight arm 70 and 55 throwing contact bar 69 to the right and in contact with the vertical row of contact points (Fig. 2). As the closing of this circuit is brought about in the first instance by the upward pressure of trolley T on lever 60 15, which is very brief in point of time, contact bar 69 is maintained in this position after trolley T has passed the lever 15, by the closing of a maintaining circuit through trolley wire W, wire 83, fuse 84, wire 85, 65 contact point 72, contact bar 74, contact

point 73, wire 86, contact point 49, contact bar 69, contact point 48, wire 79, magnet 71, wires 80, 81, and through resistance 82 to ground. At the same time, motor 14 will be operated by the closing of a circuit (Fig. 2) 70 through trolley wire W, wire 83, fuse 84, wires 85, 87, 88, movable contact point 55, contact bar 69, contact point 47, wire 89, armatures of motor 14, wire 97, contact point 45, contact bar 69, contact point 46, 75 wire 98, field of motor 14, and through wire 90 to ground. This causes motor 14 to revolve, which disengages cam 65 from roller 64, thereby permitting the weight on the link, lever, and weight arm construction 62 80 to move movable contact point 63 to the right and in line with the vertical row of contact points (Fig. 3). The continued revolution of motor 14 brings cam 61 in engagement with roller 59 on arm 60, thereby 85 moving lever 57, link 56, and movable contact point 55 carried thereby, to the right (Fig. 3), which opens the circuit to motor 14 by the withdrawal of said movable contact point 55, from contact with contact bar 90 69. The parts are so timed that the motor will come to rest when the switch is in proper position, in this case, set for the car to take the straight track. The opening of said car motor circuit also prevents heating of motor 95 14, no matter how long the circuit remains closed through magnet 71 due to a car stopping with its trolley T in contact with contactor A. When trolley T reaches second contactor B (Fig. 4) it raises lever 36 and 100 movable contact 39 engages stationary contact point 41. As movable contact 39 is electrically connected with trolley wire W a circuit is closed through stationary contact point 41, wire 91, magnet 76, wire 92, and 105 through resistance 82 to ground. The energizing of magnet 76 operates the throw-off device by raising arm 75, thereby moving contact bar 74, from engagement with contact points 72 and 73. This opens the main- 110 taining circuit which energized magnet 71 and weighted arm 70 causes contact bar 69 to move to the left. As soon as trolley T leaves contactor B magnet 76 will be de-energized. Weight arm 75 thereupon falls, 115 moving contact bar 74 to the right into engagement with contact points 72 and 73. All the contact bars now are in normal position (Fig. 1) ready to be operated by the 120 next approaching car.

Assuming next, in the embodiment illustrated, that a car approaches a switch set for the straight track, and the motorman wishes to set the switch for the curve. The car will proceed by its motive power under contactor A, with the car motor circuit closed, and as the upward pressure of trolley T raises lever 15, movable contact 18 falls into 125 engagement with stationary contact point 20 (Fig. 5) in the manner described above. 130

As said movable contact 18 is connected electrically with trolley wire W, a circuit is closed through stationary contact point 20, wire 94, contact point 53, contact bar 69, 5 contact point 54, wire 95, contact point 50, wire 96, magnet 68, wire 81, and through resistance 82 to ground. This energizes magnet 68 thereby raising weight arm 67 and throwing contact bar 66 to the left and 10 in contact with the vertical row of contact points (Fig. 5). As the closing of this circuit is brought about in the first instance by the upward pressure of trolley T on lever 15, which is very brief in point of time, contact bar 66 is maintained in this position 15 after trolley T has passed lever 15, by the closing of a maintaining circuit through trolley wire W, wire 83, fuse 84, wire 85, contact point 72, contact bar 74, contact 20 point 73, wire 86, contact point 49, contact bar 66, contact point 50, wire 96, magnet 68, wire 81, and through resistance 82 to ground. At the same time, motor 14 will be 25 operated by the closing of a circuit (Fig. 5) through trolley wire W, wire 83, fuse 84, wires 85, 87, movable contact point 63, contact bar 66, contact point 45, wire 97, armatures of motor 14, wire 89, contact point 47, contact bar 66, contact point 46, wire 98, 30 field of motor 14, and through wire 90 to ground. As the current passes through the armatures in the reverse direction from that described in connection with the first operation of the device and the current passes 35 through the motor field in the same direction as that described in connection with the first operation of the device, motor 14 will revolve in the opposite direction to that first described, which will disengage cam 61 from 40 roller 59, thereby permitting weight arm 58 to move to the left lever 57 and its link 56, thereby carrying movable contact point 55 in line with the vertical row of contact points (Fig. 6). The continued revolution of motor 45 14 brings cam 65 in engagement with roller 64 of lever construction 62, thereby moving movable contact point 63 to the left (Fig. 6) which opens the circuit to motor 14 by the withdrawal of said movable contact 50 point from contact with contact bar 66. The parts are so timed that the motor will cease to revolve when the switch has reached its proper position, in this case, set for the car to take the curve. Magnet 68 will 55 remain energized until trolley T reaches second contactor B, when the maintaining circuit will be broken at contact points 72 and 73 as illustrated and described with reference to Fig. 4. After trolley T has passed 60 contactor B, all the contact bars will be in normal position (Fig. 1).

It will be seen that when the parts are in normal position (Fig. 1), the circuit for energizing magnet 71 is closed through contact 65 point 51, contact bar 66, and contact

point 52, when said bar 66 is in normal position; and that in like manner the circuit for energizing magnet 68 is closed through contact point 53, contact bar 69, and contact point 54, when said bar 69 is in normal position. In other words, the contact bar to be moved into contact with the vertical row of contact points is moved by a circuit closed through the other contact bar when in normal position, so that when either contact bar 70 has been moved into contact with a vertical row of contact points, it is impossible to operate the other contact bar, as the movement of the first bar has made it impossible to close the circuit for so doing. Thus when 75 the switch has been thrown by trolley T engaging contactor A, the position of the switch point cannot be changed until the car has passed the switch and returned the parts to normal position (Fig. 1) by the 80 engagement of its trolley T with contactor B, even though a closely following car engages contactor A.

As an alternative arrangement for returning the parts to normal position, a shunt 90 circuit is indicated in dotted lines (Fig. 1) running from stationary contact point 41 through wire 99 to wire 81 and the ground. When trolley T passes under second contactor B, a circuit is closed through said 95 wire 99 and direct through resistance 82 to ground, and as such circuit would have practically no resistance it would shunt either magnet 68 or magnet 71, deenergizing them and causing the operating bars 66 and 100 69 controlled thereby to drop back into normal position.

Having thus described one embodiment of my invention what I claim and desire to protect by Letters Patent, is:

1. In an electric switch operating mechanism, the combination of a switch, a motor for throwing the same, a contactor ahead of said switch for operating said motor, means for controlling the operation of 110 said motor to throw said switch in one direction or another, means whereby said controlling means can be operated selectively in one of two ways through the controller of a motor car, and a second contactor adapted, through the operation of the trolley, to restore the motor controlling mechanism to normal position.

2. In an electric switch operating mechanism, the combination of a switch, a motor for throwing the same, a contactor ahead of said switch for operating said motor, means for controlling the operation of 115 said motor to throw said switch in one direction or another, means whereby said controlling means can be operated selectively in one of two ways through the controller of a motor car, a second contactor adapted, through the operation of the trolley, to restore the motor controlling 120 mechanism to normal position.

mechanism to normal position, and electrical means for maintaining said motor controlling mechanism in the position in which it is thrown by the first contactor, until the 5 trolley reaches the second contactor.

3. In a switch operating mechanism, means to control the position of a switch by the condition of the motor current in an approaching car, comprising an electrical de-

10 vice for operating said switch, means to initiate a circuit adapted to operate said device, means to provide a separate maintaining circuit for said device, and means to break said maintaining circuit when a car 15 has passed said switch.

4. In a switch operating mechanism, means to control the position of a switch by the condition of the motor current in an approaching car, comprising an electrical de-

20 vice for operating said switch, a pair of contact bars each adapted to move to close a separate circuit through said device according to the condition of said car motor current, and means to cause the operation 25 of one contact bar when the other contact bar is in inoperative position to close its respective circuit through said device.

5. In a switch operating mechanism, means to control the position of a switch by the 30 condition of the motor current in an approaching car, comprising an electrical device for operating said switch, a pair of contact bars normally in retracted position adapted to move to close separate circuits 35 through said device, and means to move one contact bar into its circuit closing position by a circuit closed through said other contact bar only when said latter bar is in normal position.

40 6. In a switch operating mechanism, means to control the position of a switch by the condition of the motor current in an approaching car, comprising an electrical device for operating said switch, means to 45 close two different circuits through said device, and stationary means in each closed circuit to prevent the closing of the other circuit while the first named circuit is closed.

50 7. In a switch operating mechanism, means to control the position of a switch by the condition of the motor current in an approaching car, comprising an electrical device for operating said switch, a vertical 55 row of contact points having two movable contact points controlling the operation of said device, means to close a circuit through said vertical row of contact points to operate said device, means on said device to 60 control the position of said movable contact points, and said positioning means.

8. In a switch operating mechanism, means to control the position of a switch by the condition of the motor current in an approaching car, comprising an electrical de-

vice for operating said switch, a pair of contact bars, a plurality of contact points normally in contact with each of said bars, and means to close a circuit through either of said contact bars and its said contacting 70 points, to move the other contact bar into position to close a circuit through said device and away from its said contacting points.

9. In a switch operating mechanism, a 75 switch, means to operate said switch comprising a motor, means to control the operation of said motor comprising stationary and movable contact points closing circuits through contact bars, and means on said 80 motor to cause the movement of a movable contact point to move it away from a contact bar and break the operating circuit of said motor.

10. In a switch operating mechanism, a 85 switch, electrical means to operate said switch comprising a first contactor, an initial circuit, and a separate maintaining and motor operating circuit, and means to break said maintaining and operating circuit comprising a second contactor.

11. In a switch operating mechanism, a switch, electrical means to operate said switch comprising a first contactor, an initial circuit, and a separate maintaining 95 and motor operating circuit, and means to break said maintaining and operating circuit comprising a contact bar and a second contactor adapted to control said contact bar to break said maintaining circuit. 100

12. In a switch operating mechanism, a switch, means to operate said switch comprising a motor and a row of stationary contact points, contact bars normally out of engagement with said contact points and each 105 in engagement with two stationary contact points, means to close selectively a circuit through one of said contact bars and its two stationary contact points to move the other contact bar into engagement with the row 110 of stationary contact points, and means to operate said motor in the desired direction by the circuit thus formed.

13. In a switch operating mechanism, a switch, means to operate said switch comprising a motor and a row of stationary contact points, contact bars normally out of engagement with said contact points and each in engagement with two stationary contact points, means to close selectively a circuit 115 through one of said contact bars and its two stationary contact points to move the other contact bar into engagement with the row of stationary contact points, means to operate said motor in desired direction 120 by the circuit thus formed comprising movable contact points adapted to be moved into and out of line with the row of stationary contact points, and means controlled by the operation of said motor to move said mov- 130

able contact point forming part of the motor-operating circuit and open said circuit when the switch has been thrown.

14. In a switch-operating mechanism, a switch, a main current supply, electrical means to operate said switch comprising means to close selectively an initial circuit from said main current supply which determines the direction of current for said electrical means, and means to close a separate circuit from said main current supply to maintain the current direction means and to operate said electrical means.

15. In a switch-operating mechanism, a switch, a main current supply, electrical means to operate said switch comprising means to close selectively an initial circuit from said main current supply which determines the direction of current for said electrical means, means to close a separate circuit from said main current supply to maintain the current direction means and to operate said electrical means, and means in said separate circuit adapted to be operated 25 to open said separate circuit when a car has passed the switch.

16. In a switch-operating mechanism, a switch, a main current supply, electrical means to operate said switch comprising means to close selectively an initial circuit from said main current supply which determines the direction of current for said electrical means, means to close a separate circuit from said main current supply to maintain the current direction means and to operate said electrical means, and means in said separate circuit controlled from a separate place on said main current supply adapted to be operated to open said separate circuit when a car has passed the switch.

17. In a switch operating mechanism, a switch, electrical means to operate said switch, means to close and open circuits to operate said electrical means only in one of two selective directions comprising means to open a separate maintaining and operating circuit and means controlled by said electrical means to determine the direction of current through said electrical means.

18. In a switch-operating mechanism, a switch, a motor to operate said switch, a row of immovable contact points, two contact bars, four immovable contact points two of 55 which are in contact with each of said contact bars and through each contact bar with each other when said contact bars are in inoperative position, a contactor adapted selectively to close a circuit through two of 60 said four contact points to move the other contact bar into contact with the row of im-

movable contact points thus opening the circuit through the two contact points normally in engagement with said moved contact bar, the movement of said contact bar closing a 65 separate maintaining circuit adapted to maintain said moved contact bar in engagement with the row of immovable contact points, and two movable contact points controlled by the position of the motor one of 70 which is adapted to close a motor operating circuit through the moved contact bar when the switch is to be thrown thereby controlling the direction of current through said motor in accordance with the position of 75 said motor and of said switch point.

19. In a switch-operating mechanism, a switch, a motor to operate said switch, a row of immovable contact points, two contact bars, four immovable contact points two of 80 which are in contact with each of said contact bars and through each contact bar with each other when said contact bars are in inoperative position, a contactor adapted selectively to close a circuit through two of 85 said four contact points to move the other contact bar into contact with the row of immovable contact points thus opening the circuit through the two contact points normally in engagement with said moved contact bar, the movement of said contact bar closing a separate maintaining circuit adapted to maintain said moved contact bar in engagement with the row of immovable contact points, two movable contact points controlled by the position of the motor one of 90 which is adapted to close a motor operating circuit through the moved contact bar when the switch is thrown thereby controlling the direction of current through said motor in 95 accordance with the position of said motor and of said switch point, and a second contactor adapted to open the maintaining circuit.

20. In a switch operating mechanism, a switch, means to operate said switch comprising a motor, two contact bars, means to move selectively either of said contact bars whereby the movement of the other contact bar is prevented and the position of the moved contact bar is maintained, means controlled by the position of the motor to determine the direction of current and the duration, if any, of said current through said motor, and separate means to return the moved contact bar to inoperative position.

In testimony that I claim the foregoing I have hereunto set my hand.

ROY VINSON COLLINS.
